UNITED STATES PATENT OFFICE.

PAUL DREW AND LESTER C. ZABRISKIE, OF RIDGEWOOD, NEW JERSEY.

DESIGN FOR A COMBINED RADIO LOUD SPEAKER AND BIRD CAGE.

Application filed September 3, 1927. Serial No. 23,293. Term of patent 7 years.

To all whom it may concern:

Be it known that we, PAUL DREW and LESTER C. ZABRISKIE, both citizens of the United States, residing at Ridgewood, in the county of Bergen and State of New Jersey, have invented a new, original, and ornamental Design for a Combined Radio Loud Speaker and Bird Cage, of which the following is a specification, reference being had to the accompanying drawing, forming part thereof.

Fig. 1 is a plan view of a combined radio

loud speaker and bird cage showing our new design.

Fig. 2 is a side elevational view of the same.

We claim:

The ornamental design for a combined radio loud speaker and bird cage as shown.

In testimony whereof we have affixed our signatures.

PAUL DREW.
LESTER C. ZABRISKIE.
